FORM FOR NECKTIES.

1,080,296.

Specification of Letters Patent.

Patented Dec. 2, 1913.

Application filed December 16, 1912. Serial No. 736,886.

To all whom it may concern:

Be it known that I, LAWRENCE W. PENNINGTON, a citizen of the United States of America, and resident of Springfield, in the county of Hampden and State of Massachusetts, have invented certain new and useful Improvements in Forms for Neckties, of which the following is a full, clear, and exact description.

10 This invention relates to improvements in a skeleton frame on which a scarf or four-in-hand necktie may be formed, tied and supported, and then engaged within a turnover collar and connected with the button 15 or stud at the front of the neck-band.

The principal object of the invention is to so construct the form, which to large extent is composed of spring wire, that in the action of engaging the form, with the tie thereon, 20 within the collar concurrently with securing its interlocking with the collar button or stud, the form, by reason of a particular character of resiliency which it possesses,—especially at its upper portion, which is 25 forced against the collar at the junction of its rear and front portions,—avoids all hard crowding effect against the collar, and saves the same from becoming distorted or disarranged as to the nicety of its adjustment 30 and "set" upon the person.

Another object is to render the application of the form, with the tied or knotted scarf thereon, upon the neck of the wearer most easy and quick of performance. And another object is to render the device one of extreme simplicity of construction and inexpensiveness of manufacture.

The invention is described in conjunction with the accompanying drawings and is defined in the claims.

In the drawings.—Figure 1 is a front view representing a four-in-hand necktie made up on the form. Fig. 2 is a front view of the form, without the necktie, shown as in its application within the front portion of a comparatively high turnover collar and interlocked with the stud,—changed positions of the parts being represented by dotted lines. Fig. 3 is a central vertical section 50 on line 3—3, Fig. 2. Fig. 4 is a rear elevation of a modified form, Fig. 5 being a central vertical section on line 5—5, Fig. 4.

Referring to the drawings, the device includes a spring wire frame comprising oppositely extending loops a a , the upper portions of which are composed of the free extremities of the wire, and extended to a lower position than the tops a^2 of the outer and partially circular portions of the loops, while the lower portions b b of said loop members are downwardly continued in separated and more or less vertical relations, and bent to produce an inwardly offset hook d , the bill portion of which is in the form of a downwardly open loop, as shown, such loop-bill portion being at its return bend d^2 contracted so as to be of an appropriate size to engage the shank x of a stud.

In addition to the frame which is made of spring wire, and as above described, the device, furthermore, includes a second frame B which may advantageously be composed as a plate of stamped out sheet metal, and this second frame has its upper portion rolled to form a tube f , the same amounting 75 in effect to an elongated and axially horizontal eye, within which the free extremities a^3 , a^4 of the wire included in the aforementioned opposite loops are engaged, and through which they are freely lengthwise 80 movable in opposite directions relatively to the frame-plate B. The said second frame or plate also has more or less nearly axially- 85 vertical eyes g g at its lateral portion at about the place where the frame portions b b adjoin the lower parts a^4 of the opposite loops a , a , so that there is an engagement and guidance of the frame portions b b with the eye-provided second frame or plate B.

By reason of the extreme resiliency possessed by the wire formed frame, and especially because of the sliding engagements crosswise of the device of the extremities a^3 of the pair of loops within and through the eye formed or tubular upper edge of the plate B, the device is collapsible or contractible most easily and in a considerable extent vertically as will be apparent on a comparison of the dotted lines in Fig. 2 with the full lines so that when the form is inserted within the collar, with the tops a^2 of the bows against the internal overturn of the collar, the upward forcing of the stud engaging loop is most readily permissible,

thereby rendering it extremely easy to interlock the loop with the stud shank without the exercise of any such force as would distort the collar or throw it out of its adjustment, or distort or break any part of the device. The spring reaction of the parts is such that immediately the pressure, applied to bring the form to its engagement or connection, is released, the form will be reliably held in its desired place.

Although it is not absolutely essential that the stud engaging hook *d* be made as the bill portion of an inwardly offset hook, (as the loop might be substantially in plane with and reentrant from the lower end of the approximately vertical and separated members *b b*), such formation is advantageous and preferable inasmuch as it gives an outward disposition of the plate or frame *B*, and a positioning of it forwardly from the surface of the collar which is borne against by the bows *a a*, as well also as forwardly of the shank of the stud which facilitates in the manipulation necessary for the engagement or removal of the form.

The frame comprised in the device composed of wire as aforesaid is made of a single length of the wire of comparatively small gage, having its intermediate portion return bent to form the hook *d*, the so bent wire being then bent to hook form, opposite portions thereof being upwardly extended in separation, then outwardly extended and bent around to form the opposite loops *a a*, the portions of which loops constituted by the extremities of the wire being extended on downwardly inclining lines and terminating in the portions *a³*, *a³*, which are arranged horizontally and alongside each other, and slidably engaged within the eye formed or tubular upper portion of the second frame *B*.

It is not deemed necessary herein to explain the manner in which the necktie or scarf is engaged and tied or knotted about the form, as the disposition of the tie may be as heretofore usual, and more or less variable to accord with the taste of the wearer.

As represented in Figs. 4 and 5, the frame plate *B* has a downward extension *h* made with an inwardly offset finger or extremity *i* to act as a closure for the downwardly open loop, to serve as a stud lock—that is as a positive locking means for preventing the disengagement of the form from the shank of the collar stud excepting by purposed manipulation.

I claim:—

1. In a neck tie form, the combination of a spring wire frame comprising oppositely extended loop members, the upper portions of which are composed of the free extremities of the wire, and extended to a lower position than the tops of the outer curved

portions of the loops, the lower portions of said loop members being downwardly continued, and bent to produce an inwardly offset hook, the bill portion of which is in the form of a downwardly open loop, and a second frame having an eye formed upper part within which the free extremities of the wire included in said opposite loops are engaged and through which they are freely movable in the direction of their lengths, said frame also having eye formed lateral parts in which the said downward continuations of the wire are engaged and relatively to which said eye formed portions may freely vertically play.

2. In a neck tie form, the combination of a spring wire frame comprising oppositely extended loop members, the upper portions of which are composed of the free extremities of the wire, and extended to a lower position than the tops of the outer curved portions of the loops, the lower portions of said loop members being downwardly continued, in opposite relations and bent to produce an inwardly offset hook, the bill portion of which is in the form of a downwardly open loop, and a second frame having an eye formed upper part within which the free extremities of the wire included in said opposite loops are engaged and through which they are freely movable in the direction of their lengths, said frame also having eye formed lateral parts in which the said downward continuations of the wire are engaged and relatively to which said eye formed portions may freely play, and said second frame having a downward extension made with an inwardly offset extremity to act as a closure for the aforesaid downwardly open loop, and to serve as a stud lock.

3. In a neck tie form, the combination of a spring wire frame comprising oppositely extended loop members, the upper portions of which are composed of the free extremities of the wire, and extended to a lower position than the outer curved portions of the loops, the lower portions of said loop members being downwardly continued, in opposite relations and bent to form a downwardly opening stud engagement loop, and a second frame having an eye formed upper part within which the free extremities of the wire included in said loops are engaged and through which they are freely movable in the direction of their lengths, said frame also having eye formed lateral parts in which the said downward continuations of the wire are engaged and relatively to which said eye formed portions may freely play.

4. A tie form consisting of a plate having a sleeve and guide eyes, a two winged tie form frame of yielding wire slidable in said sleeve and guide eyes and provided with a button engaging hook, and a mem-

ber carried by said plate to engage the button with the hook.

5. A tie form comprising a plate having a button engaging finger on one end and a 5 guide sleeve on the other end and provided with side guide eyes, and a wire form having wings slidably connected with the sleeve and a button hook slidably connected with

the eyes and adapted to coöperate with the finger in gripping a button.

Signed by me at Springfield, Mass., in presence of two subscribing witnesses.
